[57] CLAIM

The ornamental design for a bottle cap pouring device, as shown and described.

DESCRIPTION

FIG. 1 is a perspective view of a bottle cap pouring device showing my new design;

FIG. 2 is a perspective view thereof showing the pouring device in an open position;

FIG. 3 is a top plan view of the design as seen in FIG. 1;

FIG. 4 is a rear view thereof;

FIG. 5 is a front view thereof;

FIG. 6 is a side view thereof which is a mirror image of the opposite side thereof; and,

FIG. 7 is a bottom plan view thereof.
